UNITED STATES PATENT OFFICE.

ARTHUR G. WILLARD AND WILLIAM W. WILSON, OF LOS ANGELES, AND CHARLES E. WILCOX, OF EAST BAKERSFIELD, CALIFORNIA, ASSIGNORS TO SAID ARTHUR G. WILLARD AND WILLIAM W. WILSON.

WELL-BORING APPARATUS.

1,297,625.

Specification of Letters Patent. Patented Mar. 18, 1919.

Application filed November 18, 1914. Serial No. 872,748.

To all whom it may concern:

Be it known that we, ARTHUR G. WILLARD and WILLIAM W. WILSON, residing at Los Angeles, county of Los Angeles, and State 5 of California, and CHARLES E. WILCOX, residing at East Bakersfield, county of Kern, State of California, all citizens of the United States, have jointly invented new and useful Improvements in Well-Boring 10 Apparatus, of which the following is a specification.

This invention relates to well boring apparatus, and more particularly to rotary well boring apparatus, in which the boring 15 tool or device or drill is rotated through the instrumentality of a string of pipe or tubing which in turn is rotated at the mouth of the well by rotary device, or so-called table or top. The invention pertains more 20 particularly to the means for rotatively coupling the string of casing or tubing mentioned with the table or top; and it has for its object to provide means of this character which will be superior in point of relative 25 simplicity and inexpensiveness of construction, facility in assembling and handling and use, positiveness in operation and durability, and which will be generally superior in efficiency and serviceability.

30 With the above and other objects in view, the invention consists in the novel and useful provision, formation, construction, combination or association, and mode of application and relative arrangement of parts, 35 members and features, all as hereinafter described, shown in the drawing and finally pointed out in claims.

In the drawing:

Figure 1 is a vertical central transverse 40 sectional view, partly in elevation, of a part of well boring apparatus embodying the invention;

Fig. 2 is a detail horizontal sectional view of the same, taken on the line x^2-x^2 , Fig. 1, 45 and looking in the direction of the appended arrows;

Fig. 3 is a detail or fragmentary horizontal sectional view of the same taken on the line x^3-x^3 , Fig. 1, and looking in the direction of the appended arrows;

Fig. 4 is a fragmentary elevation of a modified form of construction;

Fig. 5 is a detail horizontal sectional view, taken on the line x^5-x^5 , Fig. 4, and looking in the direction of the appended arrows; 55

Fig. 6 is a plan view of a still further modified form of bushing construction embodying the invention;

Fig. 7 is a side elevation of the same;

Fig. 8 is a view similar to Fig. 6 of a still 60 further modified form of bushing construction; and

Fig. 9 is a view of the same similar to Fig. 7.

Corresponding parts in all the figures are 65 designated by the same reference characters.

Referring with particularity to the drawing, A in Figs. 1 to 3 inclusive, designates the drive stem or upper section or joint of a string through which the boring tool (not 70 shown) at the lower end of such string is handled and rotated, such drive stem being shown in Fig. 1 as being adapted to be connected by means of a collar 6 with the remaining portions of the string (not shown), 75 but which extends downwardly within the well hole which is shown cased at its top, as at 7. B in these same figures designates the improved means, in one form, for rotatively coupling the string or stem A there-

of with the rotary top or table C, such rotary top or table being mounted by means of anti-friction devices 8 upon a base or frame 9 supported at the mouth of the well hole, and having the usual central opening 80 through which the boring string is raised and lowered and within which the stem A is accommodated, such means B being applied to the stem A within such central opening, shown at 10. The table is provided with an 85

overhanging top flange 11 having an annular rack 11^a with the teeth of which meshes a gear 12 upon a shaft 13 journaled in the frame 9, and upon rotation of which shaft 13 by any suitable means for applying the 90

table C is rotated to cause the rotation of the stem A and the remaining portions of the string and boring tool through the agency of the means B. The stem A is shown as generally cylindrical in form and 100

provided with a longitudinal or vertical central bore 14 through which a liquid may be supplied to the stem and through the same to the boring zone at the boring tool 5 at the lower end of the string. The means B is shown as comprising a split bushing or halved bushing the two halves *b* and *c* of which are generally semicircular in form, and together such halves approximately fill 10 the central opening 10 in the table C, each bushing half being provided with a laterally projecting top flange portion 15 which overlaps the table or top, such flange portions together comprising a continuous annular 15 flange when the bushing halves are assembled together. Each bushing half is provided at each extremity with a vertical flange 16 which flanges are matched and joined together in pairs, a flange on each 20 bushing half being included in each such pair, and each pair of flanges is shown detachably connected together by holding means *d* which may consist of a bolt and nut or the like 17, as clearly shown in Fig. 3. 25 The bushing halves *b* and *c* are chamfered away, vertically, as at 18, to produce the flanges 16, such flanges being thus included within the generally circular geometric figure, in cross-section, of the split bushing 30 constituting the means B. The table or top C is provided with opposed channels or ways 19 formed vertically in the walls of the central opening 10, and within which are received vertical heads, ribs, or flanges 20 35 projecting laterally from the bushing halves *b* and *c* respectively, said heads or flanges 20 being capable of vertical play within the channels 19. The stem A is likewise provided with opposed vertical ways or channels or grooves 21, ranging vertically or longitudinally of the stem, and within which are received opposed vertical heads, ribs or flanges 22 formed or provided on the bushing halves *b* and *c* respectively and 40 in opposed relation, and preferably in the same vertical plane as the heads or ribs 20. The heads or ribs 22 likewise have vertical play in the channels 21. 45 The means or bushing B is applied to the stem A, one half *b* or *c* at each side of the same, and such halves are then secured together by the bolts and nuts or the like 17, this operation being performed with the stem A suitably elevated, the bushing members being applied above the table C. The bushing may then be lowered into the central opening 10 in the table, the ribs or heads 20 taking into the channels or grooves 19, and the ribs or heads 22 traversing the channels or grooves 21 in the stem A. The channels 21 preferably terminate in shoulders or stops 23 at their upper ends, and in shoulders or stops 24 at their lower ends; and upon elevation of the stem A the shoulders or 50 stops 24 will co-engage with the lower ends 65 of the ribs or heads 22 and elevate the means or bushing B from the table, so that the former may be taken apart and removed from the stem, or allowed to remain thereon and suitable means substituted therefor in the 70 opening 10 for the purpose of holding up the stem or the stem and the string and tools, or for such other purpose as may be in point in the general drilling operation and the sequence of steps entering into the same. 75 With the bushing or means B assembled and on the stem, or surrounding the same, and held in elevated position, if the stem be then lowered the bushing may be caused to interlock with the table by means of the ribs or 80 heads 20 and the channels or grooves 19, as before stated, so that rotative couple between the stem and the table, by means of the bushing B, is established. The top flange consisting of the flange portions 15, 85 resting upon the upper surface of the top or table C, holds the bushing B in working position interlocked with the table and with the stem. By means of forming the drive bushing B in two parts, detachably held together by the holding means *d*, such bushing may be readily assembled and applied to the stem, and removed from the same, laterally of the stem, or the parts may be brought together on the stem and removed 90 therefrom without passing the same over the top of the stem, which would require disconnection of the stem from the means of suspension, liquid supply and the like. 95 These means of suspension usually include a 100 swivel device the disconnection of the stem from which is undisturbed, being preferably a permanent working connection. 105 The invention therefore provides for extreme convenience and facility in applying, 110 handling and removing the bushing or means B from the string or the stem thereof. Referring to the modified form of construction shown in Figs. 4 and 5, the same general mode of operation and advantages 115 attach, but the stem D is shown as hollow and square, or in the form of a square tube, the split bushing E having two halves *e* and *f* formed the same as the halves *b* and *c*, with the opposed flanges 16, held together by holding means *d* consisting of bolts and nuts or the like 17, only the two halves *e* and *f* are formed to be brought together and detachably secured by the holding means *d* in 120 close working fit around the square stem D, eliminating any such tongues or ribs or heads as those shown at 22 in the other figures; such halves *e* and *f* having enlarged top flange portions 25 which together constitute an enlarged lateral annular top flange 125 which is devised to overlap the top or table C, and to be interlocked therewith by means of pins 26 rising from the table or top and

accommodated by suitable openings in such flange portions 25 respectively. This bushing or means E is assembled in the same manner as the bushing or means B, the halves being held together by the holding means d, and a collar or the like 27 at the lower end of the stem D serves to raise the bushing E out of the central opening in the table upon the elevation of the stem. When the bushing is lowered into place in the table, the pins 26 enter the suitable openings in the flange portion 25 and interlock the table with the stem through such bushing E. Upon elevation of the bushing E the flange portions 23 leave the pins 26.

Referring to the modified forms of bushing construction shown in Figs. 6 and 7, and in Figs. 8 and 9, the same general mode of operation and advantages attach, the same being adapted for use with a square stem such as the stem D in Figs. 4 and 5, such stem being similarly hollow, or in the form of a square tube. In the forms shown in Figs. 6 and 7, the split bushing F has two halves, g and h, the plane of junction of said halves extending diagonally from one side of the square central opening 27 at the top to the other side of such square central opening 27 at the bottom, such halves being provided with the opposed flanges 16 which are held together by holding means d consisting of bolts and nuts or the like 17. In the modified form of construction shown in Figs. 8 and 9, the plane of junction of the two halves of the bushing G, the halves being designated k and l, is entirely at one side of the square central opening 28, such halves being formed with the opposed flanges 16 held together by holding means d, consisting of bolts and nuts or the like 17. In both of these latter modified forms of construction, the stem, such as D, when the bushing is applied to the same, is gripped upon at least three sides by at least one half of the bushing, such stem being gripped upon three sides by both halves of the bushing in the form of construction in Figs. 6 and 7. This provides for more positive interlocking engagement and drive of the stem.

50 A drive bushing or means B somewhat similar to that constituting the present invention is disclosed in another application for Letters Patent of the United States for well boring apparatus, filed by William W. Wilson of us, May 29, 1914, Serial Number 841,735. Such drive bushing or the like is not, however, claimed independently in that application. Said application is now Patent No. 1,195,544, Aug. 22, 1916.

55 It is manifest that many variations from the foregoing disclosure and that of the drawing may be made in embodying the invention, without departing from a fair spirit of interpretation thereof.

Having thus disclosed our invention, we claim and desire to secure by Letters Patent:

1. In an apparatus for boring, the combination of a base, a table rotatably mounted upon the base and formed with a central opening, gearing for rotating the table, a substantially cylindrical drive bushing divided longitudinally into complementary sections adapted to be applied to the drilling stem from opposite sides thereof, the edges of the two complementary sections being provided with opposed coupling flanges, and fastening members detachably connecting the coupling flanges, the drive bushing being seated removably within the central opening of the table and having an interlocking connection therewith so as to rotate with the table.

2. In an apparatus for boring, the combination of a base, a table rotatably mounted upon the base and formed with a central opening, gearing for rotating the table, a substantially cylindrical drive bushing divided longitudinally into complementary sections adapted to be applied to the drilling stem from opposite sides thereof and to interlock therewith, the edges of the complementary sections being cut away and provided with opposed coupling flanges arranged entirely within the cylindrical confines of the bushing, and fastening members detachably connecting the coupling flanges, the drive bushing being seated removably within the central opening of the table and having an interlocking connection therewith so as to rotate with the table.

3. In an apparatus for boring, the combination of a base, a table mounted upon the base and formed with a central opening, gearing for rotating the table, a drive bushing divided longitudinally into two complementary sections adapted to be applied to the drilling stem from opposite sides thereof and formed with a rectangular opening to receive the drilling stem, the plane of junction of the two complementary sections having a diagonal relation to the axis of the bushing and extending from one side of the rectangular opening thereof to the opposite side so that each of the sections will embrace the sides of the drilling stem for the full width thereof and obtain a firm and interlocking connection with the drilling stem, and fastening members detachably connecting the complementary sections, the drive bushing being loosely seated within the opening of the table and having an interlocking connection therewith.

4. In an apparatus for well boring, the combination of a base, a table rotatably mounted upon the base and formed with a central opening, means for rotating the table, a drive bushing divided longitudi-

nally into complemental sections adapted to be applied to the drilling stem from opposite sides thereof, and fastening means rigidly connecting the complemental sections into a unitary drive bushing which is seated removably within the central opening of the table and has an interlocking connection therewith so as to rotate with the table.

In testimony whereof, we have signed our

names to this specification in the presence **10** of two subscribing witnesses.
